UNITED STATES PATENT OFFICE.

ANDREW J. CHASE, OF BOSTON, MASSACHUSETTS, ASSIGNOR TO THE KANSAS CITY PACKING AND CHASE REFRIGERATING COMPANY, OF SAME PLACE.

DESIGN FOR A REFRIGERATOR-CASING.

SPECIFICATION forming part of Design No. 20,002, dated July 8, 1890.

Application filed May 27, 1890. Serial No. 353,382. Term of patent 14 years.

To all whom it may concern:

Be it known that I, ANDREW J. CHASE, a citizen of the United States, residing at Boston, in the county of Suffolk and State of Massachusetts, have produced a new and original Design for Refrigerator-Casings, of which the following is a specification.

The object of my design is to provide a novel, handsome, and attractive casing for roll-top refrigerators; and the leading features thereof reside in a base part having front end panels and a center door, a roll-top divided into cover-sections, and a rectangular top surmounting the roll-top and having panels.

In the accompanying drawing the figure is a perspective view of a refrigerator-casing embodying my design.

In the drawing, the numeral 1 indicates the

rectangular base part, having at its front the 20 ornamental end panels 2 and central door 3 intermediate the panels. The roll-top 4 is divided into a series of cover-sections 5, 6, and 7, and is surmounted by a rectangular top 8, having its front provided with end panels 9 25 and a central door 10 intermediate such panels. The center cover-section 6 is wider than the cover-sections 5 and 7 of the roll-top.

What I claim is—

The design for a roll-top - refrigerator cas- 3c ing, substantially as shown and described.

In testimony whereof I have affixed my signature in presence of two witnesses.

ANDREW J. CHASE.
